US00D973808S

(12) **United States Design Patent** (10) **Patent No.:** **US D973,808 S**
Parsons et al. (45) **Date of Patent:** **** Dec. 27, 2022**

(54) **GOLF CLUB HEAD**

(71) Applicant: **PARSONS XTREME GOLE, LLC,**
Scottsdale, AZ (US)

(72) Inventors: **Robert R. Parsons**, Scottsdale, AZ (US); **Bradley D. Schweigert**, Cave Creek, AZ (US); **Michael R. Nicolette**, Scottsdale, AZ (US); **Caleb S. Kroloff**, Phoenix, AZ (US); **Matthew T. Andrews**, Scottsdale, AZ (US)

(73) Assignee: **PARSONS XTREME GOLE, LLC**,
Scottsdale, AZ (US)

(**) Term: **15 Years**

(21) Appl. No.: **29/841,823**

(22) Filed: **Jun. 8, 2022**

Related U.S. Application Data

(63) Continuation-in-part of application No. 29/833,450, filed on Apr. 4, 2022, which is a continuation of application No. 29/804,593, filed on Aug. 20, 2021, now Pat. No. Des. 952,086, which is a continuation-in-part of application No. 29/803,547, filed on Aug. 13, 2021, now Pat. No. Des. 952,084, which is a continuation-in-part of application No. 29/800,518, filed on Jul. 21, 2021, now Pat. No. Des. 941,946, which is a continuation-in-part of application No. 29/754,405, filed on Oct. 9, 2020, now Pat. No. Des. 954,877, which is a continuation-in-part of application No. 29/745,977, filed on Aug. 11, 2020, now abandoned.

(57) CLAIM

The ornamental design for a golf club head, as shown and described.

DESCRIPTION

FIG. 1 is a top perspective view of a golf club head according to a first embodiment;

FIG. 2 is a bottom perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is an exploded top perspective view of the golf club head according to FIG. 1;

FIG. 10 is a bottom perspective view of the golf club head of FIG. 9;

FIG. 11 is a front elevational view of the golf club head of FIG. 9;

FIG. 12 is a rear elevational view of the golf club head of FIG. 9;

FIG. 13 is a top view of the golf club head of FIG. 9;

FIG. 14 is a bottom view of the golf club head of FIG. 9;

FIG. 15 is a left side view of the golf club head of FIG. 9;

FIG. 16 is a right side view of the golf club head of FIG. 9;

FIG. 17 is an exploded top perspective view of the golf club head according to a second embodiment;

FIG. 18 is a bottom perspective view of the golf club head of FIG. 17;

FIG. 19 is a front elevational view of the golf club head of FIG. 17;

FIG. 20 is a rear elevational view of the golf club head of FIG. 17;

FIG. 21 is a top view of the golf club head of FIG. 17;

FIG. 22 is a bottom view of the golf club head of FIG. 17;

FIG. 23 is a left side view of the golf club head of FIG. 17;

FIG. 24 is a right side view of the golf club head of FIG. 17;

FIG. 25 is an exploded top perspective view of the golf club head according to a third embodiment;

FIG. 26 is a bottom perspective view of the golf club head of FIG. 25;

FIG. 27 is a front elevational view of the golf club head of FIG. 25;

FIG. 28 is a rear elevational view of the golf club head of FIG. 25;

FIG. 29 is a top view of the golf club head of FIG. 25;

FIG. 30 is a bottom view of the golf club head of FIG. 25;

FIG. 31 is a left side view of the golf club head of FIG. 25; and,

FIG. 32 is a right side view of the golf club head of FIG. 25.

The broken lines shown on the drawings form no part of the claimed design.
